ELECTRICAL FILTER

Teseo Bruno Dante Terroni, Broadgreen, Liverpool, England, assignor to Automatic Telephone & Electric Company, Limited, London, England, a British company

Application November 20, 1940, Serial No. 366,467
In Great Britain December 21, 1939

4 Claims. (Cl. 178—44)

The present invention is concerned with improvements in or relating to wave filters and has for its object the provision of a wave filtering arrangement which has a constant or substantially constant resistance for its input impedance over a range of frequencies extending from 0 to infinity cycles per second.

According to one feature of the invention a constant or substantially constant resistance wave filter comprises a unit consisting of a resistance connected in series with a filter network having a termination equal or substantially equal to said resistance, said unit being connected in parallel with a second unit consisting of a resistance in series with another filter network terminated in a resistance, the two filter networks viewed from the sides to which the series resistances are connected having iterative impedances the square root of the product of which is equal or substantially equal to each of said resistances.

According to a second feature of the invention a constant or substantially constant resistance wave filter comprises a unit consisting of a resistance connected in parallel with a filter network having a termination equal or substantially equal to said resistance connected in series with a resistance in parallel with a filter network terminated in a resistance, the two filter networks viewed from the side to which the parallel resistances are connected having iterative impedances the square root of the product of which is equal or substantially equal to each of said resistances.

The expression "filter network" as used in this specification implies series and shunt reactance elements connected in known manner to have any desired characteristics and low attenuation over one range of frequencies and high attenuation at other frequencies. Usually such a filter network includes a plurality of recurrent sectors or sections suitably related to have filter characteristics but conveniently one of the filter networks employed in accordance with the invention may consist of a single section or half section which while not quite so efficient is much less expensive and will give sufficiently satisfactory results for most purposes. If still further economy is required and the efficiency is not so important both filter networks may consist of a single section or half section.

The invention will be better understood from the following description of a number of methods of carrying it into effect, reference being had to the accompanying drawings comprising Figs. 1-10.

In the drawings

Figs. 1 to 4 show known networks illustrated to explain the principles on which the invention is based.

Figs. 5, 6 and 7 illustrate how the invention may be derived, while

Figs. 8, 9 and 10 illustrate actual embodiments of the invention.

Referring first to Fig. 1 this shows a form of anti-resonant circuit which can be arranged in known manner to present a constant pure input resistance Z at all frequencies providing:

$$R_1 = R_2 = \sqrt{\frac{L}{C}}$$

and under these conditions

$$Z = R_1 = R_2 = \sqrt{\frac{L}{C}} = \sqrt{\frac{wL}{wC}}$$

and therefore

$$Z = \sqrt{\text{product of two inverse impedances}}$$

Referring now to Fig. 2 this shows a well-known single T structure which is terminated by its mid series iterative impedances Z_{KS} and this is given by

$$Z_{KS} = \sqrt{Z_1 Z_2 \left[1 + \frac{Z_1}{4Z_2} \right]}$$

30 The T₁ structure of Fig. 3 is terminated by its mid shunt iterative impedances Z_{KSH} and this is given by:

$$Z_{KSH} = \sqrt{\frac{Z_1 Z_2}{1 + \frac{Z_1}{4Z_2}}}$$

In a filter structure such as a low pass filter, a section of which is shown in Fig. 4, Z₁ is approximately equal to jwL_0 and Z₂ is approximately equal to

$$\frac{1}{jwC_0}$$

45 (neglecting the small pure resistance components thereof), so that

$$Z_1 Z_2 = \frac{L_0}{C_0}$$

50 Hence if as shown in Fig. 5 we replace L and C of Fig. 1 by filters so that one element is replaced by a mid-series terminated filter and the other element is replaced by a mid-shunt terminated filter, the termination being such that 55 the product of the respective mid-series and mid-

shunt iterative impedance is a constant resistance which equals $R1$ and $R2$, then in Fig. 5:

$$Z = R_1 = R_2 = \sqrt{Z_{KS} Z_{KSH}}$$

$$= \sqrt{Z_1 Z_2} = \sqrt{\frac{L_o}{C_o}} \text{ (for a low pass filter)}$$

These results will still obtain in the case of a high pass filter and it will thus be seen that the constant resistance property is retained.

One filter will serve in effect as a balance filter, and it will be appreciated that a substantially constant input resistance may be obtained by utilising for the balance filter one half or more sections of the proper filter it is desired to utilise.

Reference should now be had to Fig. 6 which shows another type of constant resistance structure to which the invention can be applied and in which $Z = R$ providing $Z_1 Z_2 = R$.

If, as shown in Fig. 7 Z_2 is replaced by a mid-series terminated filter having an iterative impedance Z_{KS} and Z_1 is replaced by a balance filter having a mid-shunt iterative impedance Z_{KSH} so arranged that $Z_{KS} \times Z_{KSH} = R$, then the input impedance at the terminals 10 and 11 will be equal to R over the complete range of frequencies from 0 to infinity. The same remarks will, of course, apply if Z_1 be replaced by Z_{KS} and Z_2 by Z_{KSH} .

One practical example of the arrangement of Fig. 6 is shown in Fig. 8 where Z_2 is replaced by a shunt-derived mid-series terminated filter which is designed to give the required pass and attenuation characteristics. Leads 12 and 13 will extend via further sections of the filter to a 600 ohms termination. Z_1 is replaced by a balance arrangement which may comprise one half or more sections of the filter replacing Z_2 , the section shown being of the mid-shunt terminated series-derived type and having a 600 ohms termination. The measured input impedance curve for this arrangement is practically pure resistance with small humps near the cut-off frequency.

It will be appreciated that by increasing the number of sections in the mid-shunt terminated balance filter a better constancy of input resistance can be obtained, but the arrangement becomes correspondingly more expensive.

As an alternative, Z_2 in Fig. 6 could be replaced by a shunt derived ("m" section) mid-shunt terminated filter and Z_1 by one half or more equivalent sections of the former filter whose first section is the mid-series termination of a series-derived "m" type filter. Fig. 9 shows an arrangement of this type which utilises only one half section of balancing filter and arranged to be terminated on its far side so as to give a good matching impedance with the 600 ohms termination.

In both cases the attenuation of the filter in the pass range is increased by about 6 decibels due to the 600 ohms series and shunt resistances connected in circuit therewith; but since the shape of the characteristic curve remains almost the same, the loss is unimportant since it is a flat

loss which would normally be taken up by the amplifier.

The filter shown in Fig. 9 is preferable to that shown in Fig. 8 as it utilises less components in the balancing filter. A further example of a substantially constant resistance filter utilising a minimum number of components in the balancing filter is shown in Fig. 10.

It will be seen from this figure that the balancing filter presents an inverse impedance characteristic at the terminals 14 and 15, to that at terminals 15 and 16, and in addition the half section balancing filter is matched to the terminating resistance as closely as possible by employing a mid-shunt derived "m" type filter having an "m" of approximately 0.6.

Similarly, impedance matching at the terminals EF is maintained as closely as possible by employing a mid-shunt half section of a mid-series derived filter.

It will be appreciated that the principles described are not limited to one type of filter and they apply equally well to low pass, high pass, band pass and band elimination filters.

I claim:

1. A wave filter having a substantially constant resistance over a range of frequencies extending from 0 to infinity cycles per second comprising a unit consisting of a resistance connected in series with a filter network having a termination equal or substantially equal to said resistance said unit being connected in parallel with a second unit consisting of a further resistance in series with another filter network terminated in a resistance the two filter networks viewed from the sides to which the series resistances are connected having iterative impedances the square root of the product of which is equal or substantially equal to each of said resistances, characterised in that the filter network of one of the units consists of a single section or half-section.

2. A wave filter having a constant or substantially constant resistance over a range of frequencies extending from 0 to infinity cycles per second, comprising a unit consisting of a resistance connected in parallel with a filter network having a termination equal or substantially equal to said resistance said unit being connected in series with a second unit consisting of a resistance connected in parallel with a filter network terminated in a resistance, the two filter networks viewed from the sides to which the parallel resistances are connected having iterative impedances the square root of the product of which is equal or substantially equal to each of said resistances characterised in that the filter network of one of the units consists of a single section or half section.

3. A wave filter as claimed in claim 1 in which both filter networks consist of a single section or half section.

4. A wave filter as claimed in claim 2 in which both filter networks consist of a single section or half section.

TESEO BRUNO DANTE TERRONI.
